Jeffrey L. Costella(57) **CLAIM**

The ornamental design for a chair frame, as shown and described.

DESCRIPTION

FIG. 1 is a perspective view of new design for a chair frame as shown in the drawings;

FIG. 2 is a front elevation view thereof;

FIG. 3 is a rear elevation view thereof;

FIG. 4 is a left side view thereof;

FIG. 5 is a right side view thereof;

FIG. 6 is a top plan view thereof;

FIG. 7 is a bottom plan view thereof; and,

FIG. 8 is a perspective view with the broken lines illustrating an attached fabric seat that forms no part of the claimed design.
